United States Patent

Des. 238,342

Patented Jan. 6, 1976

238,342

WRISTWATCH

Joseph Honig, 3 Wartburg Place,
Valhalla, N.Y. 10595

Filed June 3, 1974, Ser. No. 475,362

Term of patent 14 years

Int. Cl. D10—02

U.S. Cl. D10—39

Fig. 1.

Fig. 2.

Fig. 3.

FIG. 1 is a top left perspective view of a wristwatch showing my new design;

FIG. 2 is a top plan view thereof, the bottom being plain and unornamented; and

FIG. 3 is a right side elevational view thereof.

The conventional watchband is shown broken away in all figures for convenience of illustration.

I claim:

The ornamental design for a wristwatch, substantially as shown and described.
